TABLE TOP OR SIMILAR ARTICLE

Bert J. Klein and Andre Bus, Altavista, Va., assignors to
The Lane Company, Inc., Altavista, Va., a corporation of Virginia

Application March 23, 1959, Serial No. 55,118

Term of patent 14 years

(Cl. D33—14)

The figure is a perspective view of a table top or similar article showing our design.

The broken line showing of supporting legs is for illustrative purposes only.

We claim:

The ornamental design for a table top or similar article, substantially as shown and described.
